UNITED STATES PATENT OFFICE.

CHARLES F. BATT, OF BROOKLYN, NEW YORK.

INTERNAL-COMBUSTION-ENGINE POWER PLANT.

1,309,236.

Specification of Letters Patent.

Patented July 8, 1919.

Application filed January 8, 1916. Serial No. 71,101.

To all whom it may concern:

Be it known that I, CHARLES F. BATT, a citizen of the United States, resident of and whose post-office address is 327 Jefferson Avenue, in the borough of Brooklyn, city and State of New York, have invented certain new and useful Improvements in Internal-Combustion-Engine Power Plants, of which the following is a description, reference being had to the drawings forming a part hereof.

My invention relates to prime movers and more particularly to internal combustion engines, and, in a particular form, the application for advantageous propulsion of vehicles, or in other cases where the power plant is transported with the vehicle requiring the power, or in other applications and uses as will be apparent. The adaptability of the construction it is apparent will be suitable for traction wheels or tractors, all of which come within the general class of vehicles, although they may be used for plowing, harrowing or many other kinds of work. In its commercial form my invention has a wide field of application as an entire and separate unit adapted to meet a great variety of conditions.

Among the various objects are to be noted compactness of construction, directness and simplicity of application of the power from the engine to the driven elements, and other advantages as will appear from this specification.

35 In the accompanying drawings I have shown a specific embodiment of my invention in an axle suitable for use for automobiles, in which the cylinders reciprocate within the axle housing and longitudinally with respect to the axle, delivering their power to the centrally located axle members.

This motor is a further development of the principle embodied by me in one form in application filed December 21, 1910, Serial No. 598,662, in which the form of motor was more particularly directed to its use as a stationary type with fixed foundations and in which fixed abutments resulted in movable pistons. In the present type a shaft is caused to revolve while the cylinders remain stationary, lying parallel with the shaft and radially about it, in order that the intake and exhaust arrangements may be more readily provided for.

55 In the particular form shown in the ac-

companying drawings and which I will hereafter fully describe,—

Figure I shows a part longitudinal section of the axle.

Fig. II a side elevation of the central 60 part of the axle.

Fig. III is a section at III—III of Fig. I.

Fig. IV is a transverse section at the middle of the axle.

Fig. V is a section at V—V, Fig. IV.

Fig. VI is a section on the axis of one end of the axle through the transmission mechanism.

In Fig. I the axle housing 1 is shown partly in longitudinal section, with the final axle 70 drive member 2 projecting at the right-hand end which is connected to the hub of a road wheel, preferably in the usual manner, by a clutch on the outside of the hub. In this construction the axle hub would be carried 75 on bearings on the end 3 of the housing, which is formed as a reduced portion of the housing cap or end 4, secured by bolts 5 to the main portion of the housing. The middle section of the housing 6 carries various 80 elements of the engine, and centrally supports the mechanism to convert the axially reciprocating piston motion into a rotary motion of the axially central drive shafts 7—7. The housing 1 supports the springs 85 in any usual manner, and through them, or other members which may be distance rods or radius rods, the reaction of the drive shaft is transmitted to the frame of the vehicle.

The engine comprises essentially the two opposed cylinders, formed by the interior surface of the housing at 8, in which are pistons 9, the heads 10 of which have a central hole and flange 11 fitting around the 95 tubular valve stem 12. The valve stem 12 has a collar 13, with a series of perforations 14, shown more particularly in Fig. III, while the collar 13 has a sliding fit on the shaft section 7 and abuts against the spring 15, which engages in turn a portion of the central stationary block. The valve head 16 engages a seat 17, secured to the cylinder head 18, and has perforations 19. Suitable piston rings, interior and exterior, may be 100 used as indicated. Exhaust ports are shown at 20.

The pistons are connected by the yoke 21, having bearing plates 22 and a yoke cap 23, in which a crank pin 24 engages to main- 110

tain operative relation between the yoke and the crank 25, which is integral or suitably connected with the bevel gear wheel 26, adapted to rotate on the stud 27, being held thereon by a suitable nut, as shown. A duplicate of the gear 27, is on the opposite side of the axis of the driving shaft with a duplicate of crank, crank pin and engaging yoke, which yoke forms on that side the connection between the abutting ends of the pistons. So arranged both pistons move back and forth at the same time and in the same direction, being rigid with the two yokes, and by their engagement with the pins on the cranks, the cranks are turned with each motion of the piston.

The central block which forms an anchorage for the center of the transmission mechanism between the piston and the drive shaft sections, also forms the middle section of the axle housing, and embodied in this there is built-up the following mechanism. The shell of the main casing 6, has interiorly the block 30, which is held in place by the sleeve 31, and on the intake side by the sleeve 32, while two complementary blocks 33, are bolted together by bolts 34, having at either end sleeves 35 screwed or otherwise secured to them, projecting a sufficient distance to engage the interior of the pistons at the extreme of their stroke.

Before assembling the blocks 33, there is placed on their interior the bevel gears 36 which may be supported by suitable bearings on the blocks. The hubs of said gears are fashioned with jaws which engage the sleeve 37, which is formed with clutch jaws on either end to engage either one or the other of said gears, to drive shafts 7-7 in either direction. Sleeve 37 may be in a disengaged or neutral position with respect to either of the bevel gears 36, and at the same time the sleeve 37 having a squared interior engages both abutting ends of the drive shaft sections 38. To operate sleeve 37 for engagement and disengagement at its ends with the bevel gears, a collar 39 is operated by an eccentric pin on the control rod 40, operated by a rack rod 41, engaging the pinion 42.

On the opposite side of the central housing 6, is a gas intake 43, secured by a removable cap 44, inclosing valves 45 on either side of a central partition 46, which partition diverts the incoming gases in opposite directions to the two cylinders respectively, through the ports 47.

The operation of the engine, it will now be seen, is effected by the introduction of gases through the intake 43, from any suitable carburetor, or other source, the gases passing through the valve 45 and port 47 reach the inner side of the piston 9. With the power stroke of the piston, that is the piston moving toward the central section of the axle,

the gases are compressed in the port 47 and between it and the dome of the piston, until the inner flange 11 of the piston head reaches the extreme of its stroke and abuts against the collar 13, thereby compressing the spring 15 and moving the hollow valve stem so that the head 16 will slide back on the valve seat 17, opening the perforations in the valve seat and permitting the compressed charge to pass into the explosion chamber or interior of the head of the piston. The continued motion of the engine, which at this point means an explosion in the opposite piston, then drives the first-mentioned piston on its return toward the head of the cylinder, whereupon the spring 15 insures the closing of the tubular valve on its seat 17 and the further motion compresses the charge in the cylinder head or explosion chamber, and at a suitable time the ignition by means of a spark plug 48, is effected causing the explosion and commencement of another power stroke.

When the outward movement of the piston has almost reached its limit and the engagement of the collar 13 takes place, the head 10 of the piston has reached a point where the exhaust ports 20 are opened, and the inert gases then pass out, and as shown in the drawings, exhaust into the air,— although any other suitable connections to conduct the exhaust away may be used. At the time of the exhaust however, the inlet valve is allowing the new gases, compressed so-to-speak, into the crank chamber, to pass through the valve into the cylinder head, which is shown in annular dome shape, so that the fresh gases enter at one end of the cylinder space while the exhaust gases are leaving the other end, which results in a very advantageous scavenging, particularly as the annular central inlet valve from which the gases pass toward the head wall or dome of the cylinder, insures a motion of the incoming gases to produce most effective scavenging.

Many changes may be made with respect to cooling of the cylinder head, and water-jackets may be applied in the usual manner to the outside of the cylinder or supplementary sleeves, but as described in the particular form herewith illustrated the essential elements in my combination will be clear.

The transmission of motion to the axle, it will be seen, is accomplished by the yoke 21 driving the crank pins 24, which in turn drive the gear 26, which gears are in mesh with both gears 36, and drive them in opposite directions about the longitudinal axis 125 of the axle, when the clutch 37 is shifted into position, shown in Fig. I, the left-hand gear 36 will drive the sleeve 37, and from the squared ends 38 of the two shaft sections, the drive is transmitted to the shaft section 130

7-7, and at their extremity the power is transmitted to the change speed mechanism at each end of the axle housing by means of clutch 49.

5 A transmission gear being at either end of the axle, only half of the power from the engine is transmitted through each of the gears, permitting correspondingly smaller sized parts. The transmission, 10 shown in section in Fig. VI, comprises the shell 50, keyed at one end to the end of shaft 7. The stub shaft 51 is keyed to gear 52, and at its other end runs loosely in sleeve 53, which sleeve engages and is movable on 15 the squared end 54 of the wheel shaft 2, surrounding and freely moving on the sleeve 53 is the sleeve 55 of the clutch member 56, and this clutch member with sleeve 53 may be moved axially by means of the 20 collar 57 and its groove into which the eccentric pin 58 engages, which is turned by the control stub shaft 59 and lever 60. The motion of the clutch member serves to disengage 56, with its surrounding 25 complementary clutch member 61, which in turn is part of the yoke 62, between the two portions of which are the planetary pinions in pairs 63-64, on the pinion shafts 65. Pinions 64 mesh with the central gear 30 66, which has clutch members 67 on its hub, adapted to be engaged by the clutch members at the abutting extremity of sleeve 53.

The end cap 68 of the shell 50 is secured in any suitable manner, and has the clutch teeth 69 to engage the periphery of clutch member 56, and permit slight axial motion of the clutch member when moved by eccentric pin 58 against the action of 40 the springs 70. The end cap 68 is supported in bearings 71, carried in the end portion 4 forming the end cover for the complete axle housing, and in this manner the shell 50 is supported to rotate in the axle 45 housing.

It will thus be seen that eccentric pin 58 is moved by means of lever 60, so as to withdraw the clutch member 56, then members 61 and 62 will be free to rotate with 50 the shafts and supports of the pinions 63 and 64. In this relation the drive shaft 51 drives the pinion 52 which is keyed to it and rotates pinions 63, thereby rotating pinions 64 at the same speed, but as the 55 two sets of pinions have a different number of teeth, and pinion 64 engage with gear 66, the latter will be rotated at a differential speed and by the jaw clutch members 67 it will drive the sleeve 53, which by engagement with the squared end 54 will transmit 60 the rotation to the wheel axle tube and thereby drive the road wheel. If now the movement of the clutch member 61, and thereby the shafts of the pinions 63 and 64, 65 is interrupted by bringing about a frictional

contact between the clutch members 56 and 61, the speed transmitted to the gear 66 will be varied and will constantly be increased, the more closely the speed of clutch member 61 approaches the speed or movement of 70 clutch member 56. This variation of speed is thus brought about by varying the pressure contact between the clutch members and permitting such slip as may be desired to effect the desired speed at any given time. 75 The clutch in the form shown, as to angularity of contacting surfaces, and in other respects is intended to indicate the character of the clutch with which such variation of pressure can be attained, and at the 80 same time maintain smooth running, without accidental locking of the engaging faces. When, however, it is desired to operate the road wheels at full speed, then the eccentric pin 58 is turned by the lever 60 to a position permitting the springs 70 to press the clutch members into firm engagement, and in that condition all the gears and sleeves are so locked as to turn as one, and the complete shell 50 with its internal parts rotates as a unit, and the transmission to the wheel shaft 2 is effected without the action of any gears and therefore without 85 power loss.

As shown in the drawings, it will be seen 95 that all of the parts may be mounted on their proper bearings or shafts and assembled and inserted in the casing and in the housing and locked into position, and that they may also be disassembled for inspection, replacement or repair with facility, at the same time affording in the case of transmission a completely inclosed housing which may be filled with heavy oil or grease to insure smooth running and make the mechanism substantially noiseless. 100

In Fig. V I have shown an adjustable timing switch in which the members 72 and 73 have engaging contacts in any usual form, one of them connecting to the leads of spark 110 plugs 48, and the other connecting with the leads from the battery or other source of ignition current. By means of lever 74, operated by arm 75 and shaft 76, supported in the housing, the contact may be varied to 115 vary the time of ignition.

It will thus be seen that I embody in a single rear axle unit all of the engine, and likewise the transmission,—or, in other words, the complete driving or power plant 120 for a vehicle. By the arrangement of parts I produce an axle which in shape and size conform to the permissible arrangement and dimensions of present-day practice in automobile construction. I embody therewith 125 an engine which being of the double opposed type and two-cycle, gives a substantially uniform or continuous torque effect, and by the distribution or transmission of the power direct to either wheel, in each case through 130

a separate transmission, more compact and smaller parts are made permissible. With respect to the power unit, the carrying of the rotating shaft axially through the 5 tons or through the entire engine, and the means of varying the reciprocating motion of the pistons to the rotary motion of these shafts, afford the many advantages which will be apparent in the practice of my invention.

The transmission affords a constant variation of speed from a predetermined low to a direct drive, and the same constant variation applies to the reversing by sleeve 37 and lever 40, or the engine is started in the reverse direction by shifting the timing device and giving the engine the initial movement in the direction desired, which may be accomplished by means of any suitable starting 15 apparatus attached to the supplementary shaft 77, or to such other part of the engine as may be convenient.

In any modified form a gear reverse mechanism may be used, while other modifications 25 may be made as to features or types of engine, without departing from the spirit of my invention. The parts in general are cylindrical and interfitting in such a way as to afford facilities of manufacture as well as 30 assembly. The position of parts requiring large diameter and space are concentrated at a point in the axle, namely, near the center where the increased diameter affords the necessary strength required at the mid- 35 dle of a transverse axle housing.

While numerous variations as to arrangement and dimensions, and modifications of the elements of my structure, may be made to the embodiment of my invention which I 40 have herein specifically shown and described, my invention is not limited to this particular embodiment, but what I claim and desire to secure by Letters Patent is:

1. In a self-propelled vehicle, a complete 45 powered generating and transmission unit comprising a non-revolvable axle housing, an engine embodied in said axle housing with a portion of the housing shell constituting cylinders for the engine, pistons reciprocating axially within said housing and a central axial shaft in said housing and transmission means within said housing to transmit the reciprocating motion of the pistons to the shaft.

2. In a self-propelled vehicle, a power 50 unit comprising a fixed housing, opposed cylinders comprising a portion of said housing with pistons reciprocating axially therein, a drive shaft axially disposed through the pistons, and means including gears on axes fixed to the housing for transmitting the reciprocating motion of the pistons to the rotary motion of the shaft.

3. An internal combustion engine comprising opposed reciprocating pistons in a

substantially continuous cylinder, a drive shaft extending axially through said cylinder, transmission mechanism, a housing contiguous with the engine cylinders and supporting fixed axes, gears rotatable on said axes and means connecting the same with the pistons, for the purpose described.

4. An internal combustion engine comprising a double opposed cylinder with reciprocating pistons rigidly interconnected, a 75 yoke on said inter-connection, bevel gearing located within the lateral cylindrical dimensions of said cylinder, and means to operate the same by said yoke for transmitting power to a shaft.

5. A power unit for an automobile, comprising a non-revolvable axle housing, an engine constituting a component part of said housing with pistons reciprocating axially in said housing, engaging the internal walls 85 thereof, shafts located axially in said housing and projecting beyond the ends thereof and wheels mounted thereon exterior to the housing, transmission mechanism between the cylinders and the wheels whereby 90 the speed of the wheels at each end of the housing may be varied with respect to the engine.

6. A driving unit for an automobile comprising engine cylinders located axially of 95 the driving axle and forming the axle housing, a mixture intake centrally located in said axle housing, annular opposed pistons located in said cylinders, tubular inlet valves located axially within said annular pistons 100 and means co-acting with said valves and pistons to automatically admit air to the combustion chamber of said cylinders.

7. A power unit for automobiles, comprising a stationary axle housing, road 105 wheels at opposite ends exterior to said housing, shafts projecting from said road wheels axially into said housing and a plurality of cylinders positioned between the axles and the interior walls of the housing 110 and reciprocating axially therein, and gears on axes fixed with relation to the housing to transmit the reciprocating motion of the pistons to said shafts, and change speed transmission mechanism between the pistons 115 and the road wheels.

8. A power unit having driving and driven shafts, pistons surrounding and moving parallel with the axis of one of said shafts and gears co-operating with said members and a yoke operated by said pistons adapted to rotate said gears.

9. A power unit comprising a tubular shell, pistons adapted to operate axially within said shell and a yoke actuated by 125 said pistons located centrally and adapted to reciprocate parallel to the axis of said shell, gearing actuated by said yoke and a driven shaft contained in said shell and operatively connected with said gearing.

10. In a self-propelled vehicle, an axle housing constituting a self-propelled power unit including pistons reciprocating within the walls of said housing and moving parallel with the axis of said housing, a driven shaft rotatably supported on the axis of said housing and passing through said pistons, gearing shaft supports therefor embodied in said housing laterally with respect to the driven shaft, and means connecting the reciprocating pistons with the gearing to transmit motion to the driven shaft, and a clutch within said housing to control the transmission power from said shaft, for the purpose described. 15

In testimony whereof, I have signed my name to this specification, in the presence of two subscribing witnesses, this 17 day of November, 1915.
